Inventor:

Chester A. Spotz,

by Sam Middleton Donaldson Hall

Atty.

UNITED STATES PATENT OFFICE.

CHESTER A. SPOTZ, OF GREENWICH, CONNECTICUT.

CLOSURE FOR PASTE TUBES AND THE LIKE.

Application filed April 18, 1925. Serial No. 24,208.

To all whom it may concern:

Be it known that I, CHESTER A. SPOTZ, a citizen of the United States, and resident of Greenwich, in the county of Fairfield and 5 State of Connecticut, have invented certain new and useful Improvements in Closures for Paste Tubes and the like, of which the following is a specification.

My present invention relates to improvements in closure means for collapsible tubes of the type used as containers for tooth paste, shaving cream, paints, and the like.

The invention aims to provide convenient and economical means by which a screw cap 15 may be permanently connected with the tube or container so as to be readily unscrewed therefrom and swing back out of the way, and as readily reapplied.

The invention further aims to provide, 20 in such a construction, means for suspending the tube from a hook or nail.

With these and other objects in view, the invention includes the novel features of construction and arrangement and combination 25 of parts hereinafter described, the nature and scope of my invention being defined by the claims appended hereto.

In order that my invention may be better understood, reference is made to the accompanying drawings, in which:—

Figure 1 is a side elevation of a container having my invention applied thereto.

Fig. 2 shows a vertical section thereof.

Fig. 3 is a section on line 3—3 of Fig. 2.

Fig. 4 is a perspective view of the wire attachment.

Figs. 5 and 6 are views of a modification.

Referring by reference characters to this drawing, the numeral 1 designates a collapsible tube or container of the usual form, having its head wall 1^a, of relatively rigid material provided with an externally threaded nozzle to receive the screw cap 2. This may be of the customary form except 45 that it is provided at or near its lower end with an annular flange or rib 2^a, which rib projects into or engages on opposite sides, the slots of carrying arms or members pivotally connected to the head 1^a. Preferably

50 the carrying arms are formed as parts of a single piece of wire 3, having an intermediate loop portion 3^a which pivotally engages the lug 1^b of the head 1, said lug having a groove provided with one or more elongated walls adapted to be pressed or bent over af-

ter the loop has been inserted, to retain it therein.

The wire is twisted upon itself adjacent the loop, as indicated at 3^b, and thence the respective portions are spread outwardly 60 and carried forwardly on each side of the cap and are bent backwardly and then forwardly to form loops having parallel portions 3^c having therebetween elongated openings or slots to receive the edges of the 65 flange of the cap on opposite sides thereof.

After forming these loops, the wire is brought together in front of the cap and twisted upon itself, as indicated at 3^d. The free ends of the wire are then preferably 70 turned and coiled to form a closed loop 3^e lying in a plane approximately perpendicular to the plane of the remaining portions, which closed loop serves as a convenient means for hanging the container upon a nail 75 or hook when desired.

The ends of the slot are so spaced that when they are brought in juxtaposition to the nozzle, the cap will have its threaded recess accurately aligned with the spout or 80 nozzle, while at the same time the cap may be freely revolved for screwing onto or unscrewing it from its closure position on the nozzle. When unscrewed from the nozzle it may be readily swung back out of the 85 way.

Instead of using wire for the hinged supporting means, I may use sheet metal, as shown in Figs. 5 and 6.

In this form I use a strip of sheet metal 90 4 having a central opening of a size to receive the container mouth or nozzle and an eye 4^a at one end to provide for hinged engagement with the lug on the container end. The portions of the strip lying on each side 95 of the central opening are bent up at right angles and provided with elongated slots 4^b to receive the flange of the cap.

The free end of the strip is preferably bent upward as indicated at 4^c and provided 100 with an aperture 4^d which enables it to serve as a suspending means.

Having thus described my invention, what I claim is:—

1. In a device of the class described, the combination with a tube having a threaded nozzle and a screw cap therefor provided with a peripheral flange, of hinge means for pivotally and rotatably connecting the cap to the container, comprising members lying 105

on opposite sides of the cap and having slots which receive the flange of the cap.

2. The device of claim 1, in which the hinge of the arms is in the form of a closed loop or eye, the container having a lug provided with a groove and a bendable wall for closing the groove after the loop or eye has been placed therein.

3. The device of claim 1, in which the members are brought together on the side opposite the hinge and formed into a suspending loop.

4. The device of claim 1, in which the arms are formed of wire doubled upon itself to provide the slots for receiving the flange of the cap.

5. The combination with a container hav-

ing a screw cap provided with a peripheral flange, of securing means therefor comprising a single piece of wire bent to form a closed loop, hingedly connected to the container, said wire on each side of said loop being doubled upon itself to form closed elongated slots or loops engaging the flange of the cap.

25 6. The device of claim 5, in which the wire after forming the elongated loops, is brought together and twisted upon itself and its ends coiled to form a suspending loop.

30 In testimony whereof, I affix my signature.

CHESTER A. SPOTZ.
